UNITED STATES PATENT OFFICE.

REUBEN WILLETS, OF BUTLER, PENNSYLVANIA.

GAS-ENGINE.

No. 830,270.

Specification of Letters Patent.

Patented Sept. 4, 1906.

Application filed May 26, 1905. Serial No. 262,195.

To all whom it may concern:

Be it known that I, REUBEN WILLETS, a citizen of the United States of America, residing at Butler, in the county of Butler and State of Pennsylvania, have invented certain new and useful Improvements in Gas-Engines, of which the following is a specification, reference being had therein to the accompanying drawings.

10 This invention relates to certain new and useful improvements in gas-engines, and relates more particularly to a compound or double-acting gas-engine.

15 My invention aims to provide a double-acting gas-engine wherein a novel form of cylinders is employed, the gas and air inlets and exhausts being so constructed that the pistons mounted within the cylinders will be alternately actuated.

20 The pistons of my improved engine are connected together by cross-heads and connecting-rods, in order that a positive co-operation of the pistons of my improved engine can be obtained, and by this construction and 25 operation I am enabled to greatly increase the efficiency of gas-engines and at the same time provide a strong, durable, and inexpensive engine. In connection with my improved engine I employ electric-spark igniters and have devised and put into practice 30 novel means for automatically firing each cylinder of my improved engine at predetermined times.

35 With these and many other objects in view, which will more readily appear as the nature of the invention is better understood, the same consists in the novel construction, combination, and arrangement of parts, which will be more fully described, illustrated, and 40 claimed hereinafter.

45 The essential features of the present invention involved in carrying out the objects above specified are necessarily susceptible to structural change without departing from the scope of the invention; but the preferred embodiments are shown in the accompanying drawings, in which—

50 Figure 1 is a top plan view of my improved engine, partly broken away. Fig. 2 is a horizontal sectional view of the cylinders of my improved engine. Fig. 3 is an end view of one of the electric-spark igniters. Fig. 4 is a cross-sectional view of the intermediate head of the cylinders, illustrating one of the igniters. 55 Fig. 5 is a vertical sectional view of an air and gas valve that may be employed in connec-

tion with my improved engine. Fig. 6 is a top plan view of the same. Fig. 7 is a cross-sectional view, taken on the line $z-z$ of Fig. 1, illustrating an air-valve preferably used in connection with my improved engine; and Fig. 8 is an enlarged sectional view of one of the collars employed in connection with the connecting-rods.

60 Referring to the accompanying drawings, 1 designates a suitable bed-plate carrying bearings 2 for a cranked drive-shaft 3.

65 4 designate frames carried by the bed-plate 1, which support cylinders 5 and 6 and serve functionally as guideways for connecting-rods 9 and 10, these connecting-rods being mounted within the frames 4 upon each side of the cylinders and in planes parallel with said cylinders. The ends of the connecting-rods 9 and 10 are provided with 70 cross-heads 11 and 12, the cross-head 12 being provided with a crank-pin 14, adapted to be connected to the crank 15 of the drive or driven shaft 3.

75 In Figs. 2, 3, and 7 of the drawings I have 80 illustrated the construction of the cylinders 5 and 6 of the engine, and referring to said figures 16 16 designate annular enlargements formed upon the confronting ends of the cylinders 5 and 6, and in said enlargements I 85 provide annular compartments 17 17. The cylinders 5 and 6 are connected together by an intermediate head 18, having a partial annular passage 19 formed therein, which establishes communication between the annular compartments 17 17 of the enlargements 16 16, these annular compartments serving 90 as water-jackets for the cylinders of my improved engine. A suitable water-supply may be connected to the water-jackets. 95

100 The annular passage 19 is intersected by a radially-disposed peripheral projection 20, in which two horizontally-alined openings 20' 20' are formed, and in said openings are mounted the electric-spark igniters employed to fire the cylinders 5 and 6 of the engine. One of these igniters is illustrated in Figs. 3 and 4 of the drawings, and each igniter consists of a head 21, carrying electrodes 22 and 23. The electrode 22 is 105 stationary and is insulated from the head 21 and is connected to a suitable source of electric energy. The electrode 23 is in this embodiment fixed upon a revoluble shaft 24, which is also insulated from the head 21 and is connected to a suitable source of electric energy. As this part of my igniter is com-

mon to igniters heretofore devised, I have not deemed it necessary to detail the construction of these parts or to illustrate the source of electric energy, as a conventional form of battery or generator can be readily employed. My invention in connection with the igniters resides in providing the outer end of the shaft 24 with a depending arm 25, to the lower end of which is pivotally connected a finger 26, having a beveled surface 27 and an upwardly-extending arm 28. The finger 26 is normally held in alignment with the arm 25 by a spring 29, secured to the depending arm 25, this spring normally holding the arm 28 in engagement with the arm 25. Another spring 30 is employed to normally hold the arm 25 in engagement with a stub-pin 31, carried by the head 21. The spring 30 is supported by an outwardly-extending bracket 32, also carried by the head 21. In connection with the cylinders 5 and 6 the igniters are mounted in the openings 20' 20' to fire said cylinders, one igniter being mounted upon each side of the transverse wall or partition 33 of the intermediate head 18, which serves to separate the cylinders and their respective igniters. The one side of each cylinder is provided with a longitudinally-disposed rib 34, the outer side of which extends tangential to the cylinders, and in said ribs I provide longitudinally-disposed by-paths 35 and 36, which communicate with the interior of the cylinders 5 and 6 by ports 37, 38, 39, and 40. The ribs 34 34 are provided with vertically-disposed passages 41 41, which communicate with the by-paths 35 and 36 in vertical alignment with the ports 38 and 39. In constructing the ports 38 and 39, which serve as air-inlet ports, I preferably so construct the cylinders that each port will surround a horizontal passage-way 42, which serves functionally as a gas-inlet port for the cylinders, and each gas-inlet port is adapted to be connected to a suitable supply of gas. By referring to Fig. 7 of the drawings it will be observed that the gas-inlet port is entirely independent and free of the air-inlet port 39, and the mixture or commingling of the gas and air does not take place in this instance until they have entered the cylinders. The vertically-disposed passages 41 41 are provided with air-valves 43 43, each valve consisting of a casing 44, having a spider-like frame 45 mounted therein, in which is mounted a vertically-disposed valve-stem 46, carrying a valve-head 47, which is normally held in engagement with the casing 44 by a spring 48, mounted upon the valve-stem. Diametrically opposite the gas-inlet ports 42 42 and the air-inlet ports 38 and 39 I provide the exhaust-ports 49 49, these ports being bridged, as indicated at 50 50, to support the packing-rings of pistons operating in the cylinders from entering said exhaust-ports. The outer ends of the cylinders 5 and 6 are

provided with suitable heads 51 51, carrying a conventional form of stuffing-boxes 52 52, and through said boxes pass piston-rods 53 53, the outer ends of which are connected to the cross-heads 11 and 12, while the ends extending within the cylinders 5 and 6 are provided with pistons 54 and 55. The ends of the pistons 54 and 55, confronting the partition 33 are provided with deflectors 56 56, employed to deflect the air and gas around the sides of the cylinders to the exhaust-ports. 75

In order to operate the igniters A and B at predetermined times, I have provided the connecting-rod 9 with collars C and D. In Fig. 8 of the drawings I have illustrated one 80 of the collars, consisting of a threaded sleeve 26^a, which is secured to the rod 9 by a setscrew E. Upon the sleeve 26^a is mounted the collar C, formed with an annular tapering side F, and a portion of said collar is knurled, 85 as indicated at G, to facilitate the rotating of the collar upon the sleeve. A jam or lock nut H is employed in connection with the collar to lock said collar upon the sleeve. This construction is employed in order that 90 when the collars become worn they can be readily removed and replaced by new ones, and it is possible by adjustably mounting the collars upon the sleeves to minutely adjust the same to properly actuate its respective 95 igniter. The construction of the collar D is identical with the construction of the collar C, the collar D being adapted to operate the igniter B and the collar C the igniter A. 100

The operation of my improved engine is as follows: In describing the operating of the engine reference will be had to Figs. 1 and 2, and assuming that the pistons 54 and 55 are in the position illustrated in Fig. 2 of the drawings, the igniter A is about to be actuated by the collar C, and as the air and gas admitted to the cylinder 5 has been compressed by the piston 55 the actuation of the igniter A is adapted to fire the compressed gas and air behind the head of the piston 55 and force the piston 55 to the forward end of the cylinder 5. The cylinder 6 has also been taking gas and air in the forward end of the cylinder, and simultaneously with the forward movement of the piston 55 the piston 54 is carried forward through the medium of the cross-head 11, connecting-rods 9 and 10, and cross-head 12, and the air and gas admitted to the cylinder 6 is compressed in the forward end of said cylinder adjacent to the igniter B. The forward stroke of the piston 55 permits of the gases and vapors arising from the explosion to escape through the exhaust-port 49 of the cylinder 5. The forward movement of the pistons 55 and 54 causes the collar D to actuate the igniter B, which fires the cylinder 6 and forces the piston 54 rearwardly, the piston 55 having cleared the ports 39 and 42 and received a fresh supply of air and gas in the rear end of 130

the cylinder 5, which is compressed by the rearward movement of the piston 55, and I have reached the position of the cylinders as set forth in the beginning of the operation. 5 This operation is continuous throughout the working of my improved engine, and in connection with this operation I desire to call attention to the following features. When the piston 55 is in the position illustrated in Fig. 2 of the drawings, it will be observed that the air and gas inlet ports 39 and 42 are closed, but the air-inlet port 40 is open, which permits of air passing through the by-pass 36 into the forward end of the cylinder, and 15 when the piston 55 opens the exhaust-port the air is adapted to cleanse this end of the cylinder and the exhaust-port. As the piston 55 is carried forward the air remaining in the cylinder will be partly compressed until 20 the piston 55 has uncovered the air-port 39, which permits of the air passing from the forward side of the piston to the rear side thereof, the inrush of air thoroughly commingling the gas entering the cylinder through the 25 port 42 and providing a thorough mixture within the rear end of the cylinder prior to its compression and explosion. The admission of air to the forward end of the cylinder 5 also serves to cool this end of the cylinder 30 and drive out the products of the former explosion that may remain therein. The air cooling the forward end of the cylinder, together with the water-jacket, is adapted to keep the cylinder in as cool a state as possible consistent with the explosions taking place. By the reciprocating movement of the connecting-rods 9 and 10 the igniters A and B are alternately actuated, and by adjusting the collars C and D the speed at 40 which the engine is operated can be increased or decreased. The contacting of the tapering sides F of the collars with the beveled sides of the fingers 26 26 moves the depending arms 25 25 of the igniters and causes an 45 electric spark within the cylinders, a reverse movement of the collars only actuating the fingers 26 26, the springs 30 returning the depending arms 25 to their normal position. The operation of the fingers 26 26 is obvious, 50 and in this connection I may employ other mechanical expedients for similarly operating the igniters in conjunction with the collars carried by the connecting-rods.

My improved engine may be governed by a conventional form of governor controlling the gas-supply pipe, which may admit gas to the cylinders according to the speed of the engine, the governor being actuated by the driven shaft 3. This manner of governing the 55 engine, simply controlling and varying the mixture of gas and air, does not effect the compression of the same.

In Fig. 5 of the drawings a combined air and gas valve is illustrated, which is similar 60 in some respects to the air-valve 43, with the

exception that the base of the casing 44' is provided with an annular gas-passage 45', having a suitable inlet-port 46', to which a gas-supply pipe may be connected. The admission of the gas to the engine is through a 70 port 47', which is controlled by a valve-head 48' similar to the air-valve. In lieu of employing separate and distinct gas-inlet ports I may employ the air and gas valve, as illustrated in Fig. 5. 75

While I have herein described electric-spark igniters as the preferred means of igniting the gas within the cylinders of my improved engine, it will of course be understood that various other types of igniters 80 may be employed, such as the "jump-spark," and in this connection I do not care to confine myself to a double-acting gas-engine of the type herein described operated by electric-spark igniters. 85

It is thought from the foregoing that the construction, operation, and advantages of the herein-described engine will be apparent without further description, and it will be understood that various changes in the form, 90 proportion, and minor details of construction may be resorted to without departing from the spirit of the invention or sacrificing any of the advantages thereof.

What I claim, and desire to secure by Letters Patent, is—

1. In a gas-engine of the type described, the combination of cylinders, a partitioned head mounted between said cylinders, electric-spark igniters mounted in said head 100 upon each side of the partition of said head, water-jackets surrounding said cylinders, said cylinders having air-inlet ports formed therein, said cylinders having exhaust-ports formed therein, said cylinders having gas-inlet ports formed therein, spring-pressed air-valves carried by said cylinders, pistons mounted in said cylinders and exteriorly connected together and adapted to alternately operate, means carried by the connecting parts of said pistons to alternately actuate said igniters substantially as described. 105

2. In a gas-engine of the type described, the combination with a suitable bed-plate, of 115 cylinders, a head formed with a partition and composed of a separate section of material from the cylinders and mounted between said cylinders, said cylinders having gas-inlet ports formed therein, said cylinders having air-inlet 120 ports formed therein, said cylinders having exhaust-ports formed therein, spring-pressed air-valves controlling said air-inlet ports, pistons mounted in said cylinders, rods connecting said pistons, means carried by said 125 head to fire said cylinders, and means carried by one of said connecting-rods to actuate the first-named means, substantially as described.

3. In a gas-engine of the type described, 130

the combination with two cylinders and an intermediate head formed of a separate section from said cylinders and having a central, transversely-disposed, partition and a radially-disposed peripheral projection formed with openings, of electric-spark igniters extending through said openings into said head, pistons arranged in said cylinders, rods carried by pistons and means disposed exteriorly of the pistons for connecting said rods together, and means carried by said connecting means for actuating said spark-igniters.

4. In a gas-engine of the type described, the combination of cylinders, a partitioned head mounted between said cylinders, igniters mounted in said head upon each side of the partition of said head, water-jackets sur-

rounding said cylinders, said cylinders having air-inlet ports formed therein, said cylinders having exhaust-ports formed therein, said cylinders having gas-inlet ports formed therein, spring-pressed air-valves carried by said cylinders, pistons mounted in said cylinders and exteriorly connected together and adapted to alternately operate in said cylinders, means carried by said pistons to alternately actuate said igniters substantially as described.

In testimony whereof I affix my signature in the presence of two witnesses.

REUBEN WILLETT.
